Primary Examiner — Karen E Kearney(74) *Attorney, Agent, or Firm* — Knobbe Martens Olson & Bear LLP(57) **CLAIM**

The ornamental design for a display screen with application icon, as shown and described.

DESCRIPTION

FIG. 1 is a front view of a display screen with application icon, showing the new design and,

FIG. 2 is an enlarged front view thereof, showing the application icon separate from the display screen for clarity of illustration.

The outer broken line rectangles showing the display screen and all other broken lines are included for the purpose of illustrating portions of the article and form no part of the claimed design.

1 Claim, 2 Drawing Sheets(56)
